SHIRT PRESSING MACHINE WITH LATERALLY MOVABLE HEAD

Filed Oct. 29, 1928

UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

SHIRT PRESSING MACHINE WITH LATERALLY MOVABLE HEAD

Application filed October 29, 1928. Serial No. 315,705.

This invention relates to pressing machines, particularly shirt pressing machines and has for its object a particularly simple and efficient means for moving one of the pressing elements laterally slightly during the closing of the press head in order to press the shirt close to the neck band.

The invention consists in the novel features and in the combinations and constructions hereinafter set forth and claimed.

In describing this invention reference is had to the accompanying drawing in which like characters designate corresponding parts in all the views.

15. Figure 1 is a side elevation of a pressing machine embodying my invention, the neck band holder being omitted.

Figure 2 is an enlarged fragmentary side elevation of the buck, the head and contiguous parts of the actuating mechanism or carrier for the head, the position of the head and associated parts, when the head is open, being indicated by broken lines.

20. Figure 3 is a front elevation, partly in section, of parts seen in Figure 2.

Figure 4 is a fragmentary plan view of the carrier for the head and the bearing for the link which moves the head laterally.

25. Figure 5 is a fragmentary plan view of the head showing the coaction thereof with a neck band holder and the buck.

Figure 6 is a diagrammatic view illustrating the lateral movement of the head relatively to the neck band holder as the head closes.

30. Figure 7 is an enlarged fragmentary detail view of the connection between the yoke and the head.

In pressing shirts, the neck band is fastened around or clamped against a neck band holder and in ordinary pressing machines, the head does not press close up to the neck band and the operations, if done at all, up close to the neck band, must be done by a hand iron.

35. The machine constituting the subject matter of this invention comprises, generally, upper and lower cooperating pressing elements, the lower element being provided with the usual neck band clamp at one end and the upper element with the usual cut-out complementary

to the neck band clamp, one of said pressing elements being movable toward and from the other into and out of pressing coaction and one of said elements being movable laterally endwise relatively to the other to effect relative movement of the neck band clamp and the wall of the cut-out, one toward and from the other in order to press or iron the shirt, or the bosom thereof, close to the neck band, and actuating mechanism for effecting said relative movements.

In the illustrated embodiment of my invention, the lower element or buck is stationary and the upper element or head is movable toward and from the buck into and out of pressing coaction therewith and also laterally to move the wall of the cut-out therein toward the neck band clamp when the press is going under final pressure. The head is provided with a lip at the lower edge of the wall of the cut-out, the pressing face of which lip is co-extensive with that of the head. The machine is equally useful in pressing shirts with neck bands for detachable collars and shirts with neck bands with attached collars.

1. designates the buck and 2 the head movable toward and from the buck, the buck being carried by a suitable bracket 3 which is mounted upon a frame 4 of any suitable form, size or construction.

The carrier for the head is here shown as a yoke or lever 5 pivoted between its ends at 6 to an upright 7 rising from the frame. The lever 5 carries the head 2 at its front end.

The actuating mechanism in addition to the carrier or lever 5 may be of any suitable form, size and construction, and is here shown as power actuated mechanism including an oscillating cylinder 8 having a piston movable therein, the rod 9 of which is pivoted to one arm of a bell crank lever 10 which is pivoted at 11 at its angle to the base of the frame. The other arm 12 of the bell crank lever extends upwardly and is pivoted at 13 to the lower end of a link 14 to form a toggle, the upper end of the link 14 being pivoted at 15 to the rear arm of the yoke lever 5. The piston is single acting and the press is opened, when the motive fluid is released from the cylinder 8, by countersprings 16 and 17. In

this embodiment of my invention, a check spring 18 is shown which comes into action just prior to the time the press moves under final pressure to prevent violent closing of the press.

The flow of motive fluid, as air, to and from the cylinder 8 is controlled by valve mechanism located in a casing 19. The operation of the valves is controlled by manuals as 10 a push button 20 and a release lever 21. Operation of the push button 20 permits air to enter the cylinder and actuate the piston. The valves are held in their operated position as long as desired to hold the press closed 15 by mechanism not pertinent to this invention. To open the press, the lever 21 is operated to release the valve holding means so that the press will open up under the influence of the countersprings 16 and 17.

20 The construction thus far described forms no part of this invention.

22 designates the neck band holder or clamp and 23 a cut-out in the head complementary to the clamp. There are various types of neck 25 band holders. In some types of neck bands, a movable clamp member or loop 24 is used to press the neck band against the base or block of the neck band holder. In another 30 type, the neck band is merely buttoned around the block. This block may also have the usual expanding clamp. As the operation of the various types of neck band holders is well known and as the construction of a neck 35 band holder is not pertinent to this invention, further description is thought to be unnecessary.

In the illustrated embodiment of my invention, the yoke lever 5 is bifurcated or double and the head 2 has ears 25 and 26 at 40 its ends in which is fixed, as by keys 27, a shaft 28, this shaft extending lengthwise of the head along the median line thereof, and the yoke is provided with brackets 29 and 30 at the ends of the bifurcations, these brackets 45 being loosely mounted on the shaft 28 to permit the shaft and the head to move endwise and also to have a slight compensating rocking movement. Such rocking movement of the head is desirable to permit the head to 50 move relatively to the yoke and compensate for different thicknesses of the work overlying different portions of the buck so that the head presses uniformly throughout the pressing face of the buck.

55 The rocking or compensating movements of the head are resisted by spring connections between the brackets 29 and 30 and the head. There are two spring connections 31 at one 60 end of the head, and but one spring connection 32 at the other end. Each spring connection includes a stud 33 extending upwardly from the head through a slot 29^a in the bracket 29 or 30 and having a shoulder as a nut 34 at its upper end, and a spring inserted 65 between the nut 34 and the bracket 29 or 30,

the spring encircling the stud above the bracket. The stud 33 is connected at its lower end by a pivoted joint as a ball and socket joint 33^a and is likewise connected to the bracket 29 or 30 by a similar joint 29^a, the latter being provided by a spherical boss 29^b, Figure 7, on the seat 31^a for the spring 31 or 32. The boss 29^b seats in the slot 29^c. These pivotal or universal joints at 33^a and 29^b permit the head to shift laterally relatively to the yoke lever 5.

The means for moving the head laterally is here illustrated as cam members 36 and 37, the cam member 36 being fixed to the shaft 28 as by a key 38 and the cam member 37 being mounted to rock about the shaft 28 and being held from endwise movement by a spacing sleeve 39 surrounding the shaft 28 and interposed between the cam member 37 and the bracket 29. The cam members have coacting cam faces or lifts on their opposing sides. The cam member 37 is provided with a rock arm 40 and when this arm 40 is rocked, the cam face of the member 37 will thrust against and ride up the cam face of the member 36 thus shifting the head laterally. This lateral movement is against the returning action of a spring 41 interposed between the cam member 36 and the bracket 30.

The rock arm 40 is actuated during the closing of the press by a link 42 extending lengthwise of the lever 5 or between the bifurcations thereof, and pivoted at its front end at 43 to the arm 40 and near its rear end at 44 to a bracket 45 rising from the bearing 5^a in which the pivot pin 6 of the yoke lever is mounted. The length of the link 42 is different, preferably less than the length of the front arm of the yoke 5 so that during the movement of the press head, the arm 40 will be rocked due to the differential movement of the link 42 and the yoke lever 5. Preferably, the link 42 is not pivoted directly to the bracket 45 but slides endwise in a sleeve 46 which is pivoted between the bifurcations of the bracket 45, and the endwise movement of the link 42 during the closing of the press is resisted by a spring 47 interposed between the rear end of the sleeve 46 and adjustable abutment or nut 48 on the rear end of the link 42. Also the link 42 is acted on by a spring 49 weaker than the spring 47 and acting in opposition thereto, the spring 49 being interposed between a cross bar 50 which connects the bifurcations of the yoke lever 5, and shoulder 51 on the rod 42 in front of this cross bar 50.

In order to facilitate the ironing or pressing of the shirt close up to the neck band, especially when the neck band clamp is used embodying a loop which overhangs the portion of the shirt adjoining the neck band, the head is provided with a lip 52 along the lower side of the wall of the cut-out 23, this lip tucking under the loop 24 or pressing the

shirt up close to the neck band without having the wall of the cut-out press against the neck band. The lip has a pressing face which is an extension of the pressing face of the head.

When the press is open, as indicated in dot dash lines in Figure 2, the spring 49 holds the link 42 in its forward position so that the arm 40 is in such position that the high points of the cam 37 rest on the low points of the cam 36. As the press head closes the pivotal connection 43 describes a different arc than does the shaft 28. This difference in the arcs described is due to the fact that the lever 5 and link 42 are different lengths and are pivoted to rotate about different centers. The movement of the lever 5, as the press closes, will cause the link 42 to rotate the arm 40 and cam 37 so that the cam 36 will be thrust to the right, in Figure 3, to slide the head laterally toward the neck band holder. The force with which the link 42 rotates the arm 40 and cam 37 will depend on the amount of compression of the spring 47 during the endwise movement of the link 42. The nut 48 provides means for adjusting the tension of the spring 47, and this spring 47 renders the means which thrust the head laterally yieldable so that no damage will result if the lip 52 contacts with the neck band holder before the pressing jaws are together under final heavy pressure. As the head approaches the buck, it moves successively into positions A, B, C, D and E where it is close to the work on the buck and under little or no pressure. During the final movement of the head from position D to position E, the lip 52 moves close up to the neck band.

What I claim is:

40 1. In a shirt pressing machine, the combination of a supporting frame, upper and lower pressing elements, the lower pressing element being provided with a neck band clamp at one end, the neck band clamp projecting above the pressing surface of the lower element and the upper element being provided with a cut-out complementary to the neck band clamp, a lever pivoted to the frame and carrying the upper element, one of said 45 elements being movable laterally endwise relatively to the other to effect relative movement of the neck band clamp and the wall of the cut-out, one toward and from the other, mechanism for effecting the lateral movement of the laterally movable element comprising a rocking cam, a link extending in a direction lengthwise of said lever and movable up and down therewith and pivoted 50 to the frame at a point spaced apart from the pivot of the lever so that the link is of different length and rotates about a different center than the lever, the link being connected to said rocking cam mechanism for actuating 55 the lever, and a follower coacting with the

cam and connected to the laterally movable element to transmit motion thereto.

2. In a shirt pressing machine, the combination of a buck having a neck band clamp at one end, said neck band clamp projecting above the pressing surface of the buck, a head movable toward and from the buck and also laterally endwise of the buck toward and from the neck band clamp, the head having a cut-out complementary to the clamp, common power means for actuating the head toward and from the buck and yieldingly moving it laterally to press the wall of the cut-out in the head close to the neck band clamp and thereby pressing the shirt close up to the neck band.

3. In a shirt pressing machine, the combination of a buck having a neck band clamp at one end projecting above the pressing surface of the buck, a head movable toward and from the buck and also laterally endwise of the buck toward and from the neck band clamp, the head having a cut-out complementary to the clamp, a movable carrier for the head, the head being movable laterally relatively to the carrier and endwise of the buck, to carry the wall of the cut-out toward and from the neck band clamp and yieldable means operable automatically by the closing movement of the head to move the head laterally during the last part of the closing movement.

4. In a shirt pressing machine, the combination of a buck having a neck band holder at one end projecting above the pressing surface of said buck, a head movable toward and from the buck, the head having a cut-out complementary to the neck band holder, a movable carrier for the head, the head being movable laterally relatively to the carrier endwise of the buck to carry the wall of the cut-out toward and from the neck band holder and means operable automatically by the closing movement of the head to move the head laterally during the last part of the closing movement, said means comprising cams movable up and down with the head, one cam being fixed to move endwise therewith, and the other being fixed from endwise movement relatively to the carrier, and yieldable means for automatically moving the latter as the head approaches closed position.

5. In a shirt pressing machine, the combination of a buck having a neck band clamp at one end projecting above the pressing surface of said buck, a head movable toward and from the buck and also laterally endwise of the buck toward and from the neck band clamp, the head having a cut-out complementary to the clamp, a movable carrier for the head, the head being movable laterally relatively to the carrier endwise of the buck to carry the wall of the cut-out toward and from the neck band clamp, yieldable means

operable automatically by the closing movement of the head to move the head laterally during the last part of the closing movement, and spring means for returning the head laterally.

6. In a shirt pressing machine, the combination of a buck having a neck band clamp at one end projecting above the pressing surface of said buck, a head movable toward and from the buck and also laterally endwise of the buck toward and from the neck band clamp, the head having a cut-out complementary to the clamp, a movable carrier for the head, the head being movable laterally relatively to the carrier to carry the wall of the cut-out toward and from the neck band clamp, means operable during the closing movement of the head to move the head laterally at the end of the closing movement, said means comprising cams movable up and down with the head, one cam being fixed relatively to the head to move endwise therewith, and the other being fixed relatively to the carrier, and yieldable means for moving the latter as the head approaches closed position, and spring means for returning the head laterally to its original position when the press opens.

7. In a shirt pressing machine, the combination of a supporting frame, a buck on the frame having a neck band clamp at one end, a head movable toward and from the buck and also laterally endwise of the buck, the head having a cut-out complementary to the clamp, a carrier pivoted to the frame for the head, the head being movable laterally relatively to the carrier, means for moving the head laterally comprising a rocking cam member associated with the carrier, and a cam member associated with the head and coacting with the rocking cam member to shift the head laterally during the movement of the rocking cam member, a link pivoted at one end to said rocking cam member and extending toward the pivot of the carrier and being pivoted to the frame at a point spaced apart from the pivot of the carrier, so that the link rotates about a different center than the carrier whereby during the movement of the carrier, said rocking cam member is actuated by the differential movement of the carrier and the link.

8. In a shirt pressing machine, the combination of a buck having a neck band clamp at one end, a head movable toward and from the buck and also laterally endwise of the buck, the head having a cut-out complementary to the clamp, a pivoted carrier for the head, the head being movable laterally relatively to the carrier, means for moving the head laterally comprising a rocking cam member associated with the carrier and means associated with the head and coacting with the rocking cam member to shift the head laterally during the movement of the rocking cam member, a link pivoted at one end to said

rocking cam member and extending toward the pivot of the carrier and being pivoted at a fixed point spaced relatively to the pivot of the carrier, so that the link rotates about a different center than the carrier whereby during the movement of the carrier, said rocking cam member is actuated by the differential pivotal movement of the carrier and the link, a spring for resisting the endwise movement of the link during the closing movement of the head.

9. In a shirt pressing machine, the combination of a supporting frame, a buck carried by the frame and having a neck band clamp at one end, a head movable toward and from the buck and also laterally endwise of the buck, the head having a cut-out complementary to the clamp, a carrier pivoted to the frame for the head, the head being movable laterally relatively to the carrier, means for moving the head laterally comprising a rocking cam member associated with the carrier and a cam member associated with the head and coacting with the rocking cam member to shift the head laterally during the movement of the rocking cam member, a link pivoted at one end to said rocking cam member and extending toward the pivot of the carrier and being slidably pivoted to the frame at a point spaced apart from the pivot of the carrier whereby the link rotates about a different center than the carrier and said rocking cam member is actuated by the differential pivotal movement of the carrier and the link, a spring for resisting the sliding endwise movement of the link during the closing movement of the head, and an additional spring acting on the link in opposition to the first spring and being weaker than the first spring.

10. In a shirt pressing machine, the combination of a supporting frame, a buck carried by the frame and having a neck band clamp at one end, a head movable toward and from the buck and also laterally endwise of the buck toward and from the neck band clamp, the head having a cut-out complementary to the clamp, a lever carrying the head, a shaft extending transversely of the lever and slidably mounted therein, the head having ears fixed to the shaft, a cam on the shaft, a second cam rotatably mounted on the shaft and coacting with the first cam, the second cam having a rock arm, means for holding the second cam from axial movement and a link extending lengthwise of the lever and pivoted at one end to the rock arm and at its other end to the frame at a point spaced from the axis of the lever.

11. In a shirt pressing machine, the combination of a frame, a buck carried by the frame and having a neck band clamp at one end, a head movable toward and from the buck and also laterally endwise of the buck toward and from the neck band clamp, the

head having a cut-out complementary to the clamp, a lever carrying the head, a shaft extending transversely of the lever and slidably mounted therein, the head having ears 5 fixed to the shaft, a cam fixed on the shaft, a second cam rotatably mounted on the shaft and coacting with the first cam, means for holding the second cam from axial movement, a link extending lengthwise of the lever and 10 pivoted at one end to the rotatable cam and at its other end slidably pivoted to the frame at a point spaced from the pivot of the lever, so that the link rotates about a different center than the lever, the link being slidably 15 mounted relatively to the pivot, and spring means for resisting the sliding movement.

12. In a shirt pressing machine, the combination of a buck having a neck band clamp at one end projecting above the pressing surface of said buck, a head movable toward and from the buck and also laterally endwise of the buck toward and from the neck band clamp, the head having a cut-out complementary to the clamp and also having a laterally extending lip along the lower edge of the cut-out and projecting into the cut-out for pressing the shirt close up to the neck band, the lip having a pressing face forming an extension of the pressing face of the head, 20 and means for actuating the head and moving it laterally toward the neck band clamp during the closing operation of the head.

13. A shirt pressing machine including cooperative pressing elements; a neck band holder adjacent one end of one of the pressing elements, the other pressing element being formed with a cut-out portion complementary to the neck band holder; means for moving one of said pressing elements toward and 25 from the other to close and open the press; and automatic, yieldable means for moving one of said pressing elements laterally with respect to the other to bring the edge of the cut-out portion of the upper pressing element 30 close to the neck band clamp.

14. A shirt pressing machine including cooperative pressing elements; a neck band holder adjacent one end of one of the pressing elements, the other pressing element being 35 formed with a cut-out portion complementary to the neck band holder; means for moving one of said pressing elements toward and from the other to close and open the press; automatic mechanism for moving one of the 40 pressing elements laterally as the elements come together under heavy pressure; and adjustable means to control the force exerted by said mechanism.

15. In a garment or laundry pressing machine cooperative pressing elements one of which is movable with respect to the other to open and close the press; operating mechanism for the movable pressing element; means for moving the pressing elements laterally with respect to one another as they

come into final pressing contact, including a cam rotatable with respect to the laterally movable element; means operated by the opening and closing movement of the movable element to impart such rotary movement 70 to the cam; and a cam follower connected to the laterally movable element.

16. A shirt pressing machine including cooperative pressing elements; a neck band holder adjacent one end of one of the pressing elements, the other pressing element being formed with a cut-out portion complementary to the neck band holder; means for moving one of said pressing elements toward and from the other to close and open the press; and means, connected with a fixed point on the pressing machine and connected with one of the pressing elements, for moving that pressing element laterally with respect to the other during the final closing of the press. 75

17. A shirt pressing machine including cooperative pressing elements; a neck band holder adjacent one end of one of the pressing elements, the other pressing element being formed with a cut-out portion complementary 80 to the neck band holder; means for moving one of said pressing elements toward and from the other to close and open the press; yieldable means to move one of said elements laterally endwise relatively to the other to move the wall of the cut-out portion toward and from the neck band holder; a lip around the wall of the cut-out portion, said lip forming an extension of the pressing face of the pressing element which is formed with said 85 cut-out portion.

18. In a garment or laundry pressing machine cooperative pressing elements one of which is movable with respect to the other to open and close the press; operating mechanism for the movable pressing element; means for moving the pressing elements laterally with respect to one another; actuating mechanism for said laterally moving means, including means mounted on the frame and connected with one of said pressing elements and operable by change in position of the movable pressing element and operable independently of the pressure exerted between the pressing elements. 90

In testimony whereof, I have hereunto signed my name, at Syracuse, in the county of Onondaga, and in the State of New York, this 25th day of October, 1928.

ERNEST DAVIS.
